(57) **CLAIM**

The ornamental design for a suction hood as shown and described.

DESCRIPTION

The patent or application file contains at least one drawing executed in color. Copies of this patent or patent application publication with color drawing(s) will be provided by the Office upon request and payment of the necessary fee.

1. Suction hood

1.1 : Front

1.2 : Back

1.3 : Left

1.4 : Right

1.5 : Top

1.6 : Bottom

1.7 : Perspective

Color forms no part of the claimed design. The portion of the suction hood shown as a solid black rectangular feature in 1.1 and 1.7 forms no part of the claimed design.
